UNITED STATES PATENT OFFICE.

CHARLES HAHLO, OF MANCHESTER, ENGLAND.

HAT AND SWEATBAND OR LEATHER TO BE USED THEREFOR.

1,359,502.

Specification of Letters Patent. Patented Nov. 23, 1920.

Application filed July 27, 1915. Serial No. 42,232.

To all whom it may concern:

Be it known that I, CHARLES HAHLO, a citizen of Great Britain, and resident in the city of Manchester, in the county of Lancaster, England, have invented certain new and useful improvements in Hats and Sweatbands or Leathers to be Used Therefor, of which the following is a specification.

10 My invention relates to improvements in the construction and formation of sweatbands or leathers for hats and has for its object to provide means for increased ventilation to the head of the wearer greater and 15 better facilities for fitting and increased gripping power to the head. In order that my invention may be more fully understood I append hereto the following drawings, in which like letters of reference refer to the 20 same parts in each drawing, Figures 1 to 4 inclusive.

Fig. 1 is a plan of a hat interior showing the sweatband turned outward at one portion to show the arrangement and disposition of the ventilation perforations.

Fig. 2 is a longitudinal sectional view of a hat showing the sweatband and perforated ventilation strip in position, also the annular air space between the sweatband and the hat body interior.

Fig. 3 is a plan of part of the back interior portion of a hat tilted up in perspective showing the perforated ventilation strip stitching edges, where it is secured to the hat body and to the sweatband, it also shows the ventilation perforations in the ventilation strip.

Fig. 4 is an enlarged vertical section through a portion of the brim, body and crown of a hat, showing the method of ventilating the interior of the hat.

To carry out my improvements, I attach by suitable means to the bottom inner side of the sweatband *b* and *b*¹, between the 45 sweatband and the hat body *d*, a strip of dyed or undyed leather *a*, the upper edge being secured to the sweatband at *b*¹ and the lower bell shaped edge *c* forming a stitching edge is secured to the hat body *d* by means of the usual fabric or stitching 50 tape *c*¹ attached thereto; midway between the stitching edge *c* and the lower edge of the sweatband *b* and extending around the whole circumferential or annular surface of 55 the strip of leather *a*, a chain of perforations or air passages *e* are provided, through

which cool air may pass into an air annulus *f* *f*¹, formed between the hat body *d* and the sweatband *b*. This air annulus extends around and between the entire inner circumference of the hat body *d* and the sweatband *b*, and is formed by means of a suitably increased thickening up of the perforated ventilation strip *a* at or near its upper extremity at *b*¹ where secured to the 60 sweatband *b* next the hat body; this ventilation strip *a* is preferably made in a bell shaped form below the sweatband *b* in order that the stitching edge *c* may form its maximum circumference, the annular ring 65 of air passages or perforations *e* form its mean, and the upper edge or surface at *b*¹, where secured to the sweatband, may form such a suitable minimum circumference as to provide and form the requisite air annulus or ventilating passage *f* *f*¹ when attached to the sweatband in the manner shown; suitable and ample perforations *e* are provided to admit a full and free flow 70 of cool air into the annulus and thence to 75 the hat crown *g*. Greater and better facilities for fitting are provided by means of the air annulus *f* *f*¹, due to its easy yielding properties under pressure applied to the sweatband *b* when pressed in contact with 80 the head of the wearer; by this easy yielding cushion-like surface imparted to the sweatband, a general and complete contact with the head of the wearer is secured. The increased gripping power of the sweatband 85 *b* is obtained by means of the readiness and freedom with which the sweatband *b* establishes a rapid and entire contact with the head, as the air cushioned surface of the sweatband offers no local surface points of 90 resistance when pressed upon the head, thus, a general and a firm grip is easily obtained by the sweatband when the hat is 95 pressed into position on the head of the wearer; at the same time the free, full flow 100 of cool air through the whole chain of the perforations *e* in the ventilation strip *a* to the annulus *f* *f*¹ and to the hat crown *g* is in no way thereby impeded or impaired. The passage or flow of ventilation air is indicated on the drawings by means of arrows.

Having now particularly described and ascertained the nature of my said invention and in what manner the same is to be performed, I declare that what my claim is:

1. In a device of the character described

a hat body having a brim, a flexible sweat band within the body in spaced relation with the same with its lower edge above the plane of the hat brim, in combination with 5 a flexible bell-shaped strip of leather secured at its outwardly flared lower edge portion to the hat body at the juncture of the same with the brim, the upper portion of the said leather strip being extended vertically and thickened for attachment to the 10 inside of the sweat band and provided with an annular space or air annulus between the sweat band and the hat body, and the intermediate portion of the leather strip below 15 the lower edge of the sweat band being provided with a plurality of perforations forming air passages in said bell-shaped strip communicating with the said air annulus,

said leather strip yieldably supporting the sweat band in spaced relation with the hat 20 body and adapted to yield with the same under pressure applied to the sweat band to conform to the head of the wearer.

2. In a hat, the combination of a hat body, a flexible strip of leather of bell- 25 shape formation stitched at its lower edge to the inside brim of the hat body, said flexible strip of leather being provided with perforations, and a sweat band secured to the upper edge of said leather and above the 30 plane of attachment of the bell-shape leather to the hat body, said sweat band being spaced apart from the inside wall of the hat body to provide an air space.

CHARLES HAHLO.
